MEANS FOR PRODUCING KNITTED FABRICS

Thomas Henry Jones, Woodthorpe, and Robert Kirkland Mills, Sherwood, Nottingham, England, assignors to Hosiery Developments Limited, Nottingham, England

Application December 23, 1935, Serial No. 55,898
In Great Britain June 11, 1935

4 Claims. (Cl. 66—123)

This invention relates to the means for producing knitted fabrics; an object of the invention being to facilitate the production in such fabrics of spread loops, that is to say loops which laterally extend over a plurality of stitch wales; the incorporation of such spread loops providing openwork or pattern effects in the fabric and also increasing the resistance to laddering. Another object of the invention is to provide a novel and simplified method of effecting loop transference during the manufacture of knitted fabric.

By this invention there is provided a needle having a loop-displacing lateral projection, in the side of which adjacent to the needle-stem there is a lateral loop-receiving recess the purpose of which is to receive the loop so that strain on it (such as would otherwise result from its distention by the projection) is avoided, the lower edge of which recess serves to terminate the movement of the loop down the needle-stem.

In order that the invention may be better understood reference will now be made to the accompanying drawings, in which

Figure 1 shows in three-quarters side elevation a preferred construction of needle.

Figure 2 shows a tongue slightly modified from that of Figure 1.

Figure 3 is a section taken on the line 3—3 of Figure 1, looking in the direction of the arrows.

Figures 4—7 illustrate stages in the manufacture of fabric by the aid of a needle according to this invention.

Throughout this description, like reference numerals indicate like parts.

In the drawings, it has been elected to illustrate a latch needle, although it will be readily understood, the invention is also applicable to bearded needles. The needle is provided on its stem 10 a suitable distance below the latch 11 (or below the beard in the case of a bearded needle) with a tongue piece 12, the outer edge 12a of which gradually diverges from the line of the stem. In effect, therefore, the tongue gradually widens downwardly, i. e. away from the hooked end 13 of the needle. The said divergence, or downward taper, is such that at the base of the tongue the outer edge 12a thereof overlaps the front of the next adjacent needle when the needle according to this invention is installed in a knitting machine. It will be seen that the tongue 12 projects or curves laterally from the front edge of the needle stem, so that the said adjacent needle may be projected be-

hind it and so that it does not foul the trick wall.

The said tongue may be constituted in effect by a tongue or wing that, when the needle is blanked out, extends in the plane thereof forwardly from the front edge and during subsequent stages of the manufacture is bent sideways. In any case, there is a recess 14 at the side adjacent to the needle stem. The purpose of this recess is to avoid excessive lateral distension of the needle loop cleared down onto the tongue and as will be realized from an inspection of Figure 4 such a recessed tongue serves to displace the loop sideways rather than to distend it as would a solid non-recessed tongue. The edge 14a of this recess is substantially parallel with the edge 12a.

When the tongue is recessed, instead of producing it by blanking out the needle from sheet material, it may be produced by bending and twisting the flat needle stem. Such a construction is shown in Figure 2. It will be seen that the stem diverges (and is twisted) from the straight line to give the inclined outer edge 12a and the recess 14, is then bent laterally back towards the general plane of the stem as at 12b, and is finally bent backwards in the said plane as at 12c. Whatever the construction of the tongue, however, it is preferred that it shall be somewhat curved in cross-section or plan, as shown in Figure 3, as distinct from projecting sharply at right angles to the plane of the stem.

The utilization of a needle as above to produce a spread loop will now be described with reference to Figures 4—7, on a machine employing independently operable needles. Assuming that the needles have been retracted to knock over and are carrying the last formed stitch loops S¹, S² in their hooks, a needle 10 with a tapered tongue piece 12 as before described is by suitable means projected or raised and in so doing the stitch loop S¹ thereon is cleared down the stem or shank of needle 10 and passes on to the tapered tongue. This causes the loop to be gradually spread or displaced laterally and the upward movement of the needle is continued until the widest portion of the tongue is approximately level with or slightly above the top of the next adjacent needle, when the spread or displaced loop S¹ will be extended over said adjacent needle 10¹ when its downward movement in relation to the needle stem is arrested by the lower, horizontal and laterally-extending, boundary 15 of the recess. The last named needle 10¹ is now raised or projected, and in so doing same passes through the spread loop 55

and said loop is received on the shanks of the two adjacent needles, Figure 5. Subsequently new thread is fed into the needle hooks, Figure 6, and the spread loop is cast off (Figure 7) in 5 the known manner so as to extend across two adjacent needle wales of the fabric.

If, instead of producing a spread loop it is desired to transfer a stitch loop from one needle to another, the aforesaid movements are carried 10 out in so far as the spreading of the loop over the two needles is concerned, but instead of retaining the spread loop on the two adjacent needles, the first needle from which the loop has been spread is lowered or retracted sufficiently to cast off the loop which is thus transferred 15 to the next adjacent needle.

Thus it will be seen that the invention provides a process of producing in knitted fabrics spread loops and/or transferred loops by the simple operation of displacing adjacent needles relatively 20 to each other without the employment of additional instruments.

When employing spring or bearded needles for stitch transference it will of course be understood 25 that the beard of the needle from which the loop is to be transferred must be pressed to permit casting off.

As previously intimated fabrics having ladder-proof properties can be produced by the incorporation of spread or transferred loops, and 30 various types of locked stitch fabric can be produced by the means above-described. For example, fabric can be knitted with spread loops at every stitch wale and in every knitted course. Alternatively, courses embodying spread loops 35 may alternate with courses without such loops, and the spread loops may be formed on alternate needles (alternate stitch wales), say, for example, first on odd needles and then on even needles. In another arrangement spread loops may be 40 made on alternate needles or alternate needle

groups at alternate courses and on the remaining alternate needles or groups at the other alternate courses. Additionally, the needles may be so operated that a loop, after being spread over two needle wales, is carried forward to form an intermeshing stitch loop in at least one of said wales. 5

We claim:—

1. A hooked knitting needle having the stem, 10 below the hook, diverging laterally from the straight line, and then returning, wherein the return portion has its upper edge substantially normal to the general line of the needle stem to form a stop for a needle loop cleared down the stem onto the diverging portion. 15

2. A hooked knitting needle, having an integral, 20 downwardly-tapered loop-displacing part projecting laterally from the stem at a location below the loop for displacing laterally a loop cleared down the stem onto it, a lateral recess in that side of the said part that is adjacent to the stem for receiving said displaced loop, and a lower edge to said recess for terminating the downward movement of the loop on the stem. 25

3. A hooked knitting needle, having at the front 30 edge of its stem, below the hook, a local lateral divergence of said stem for displacing laterally a loop cleared down the stem onto it, which divergence terminates in a return part the upper edge of which is substantially normal to the length of the stem, for arresting the downward movement of the loop along said divergence. 35

4. A hooked knitting needle, the stem of which, 40 below the hook, diverges forwardly and laterally from the general line of said stem to cause formation of a thread loop spread and laterally deflected, and then returns abruptly, laterally and backwardly, to said general line to form a stop for the said loop. 45
